UNITED STATES PATENT OFFICE.

FRANCIS H. RICHARDS, OF SPRINGFIELD, MASSACHUSETTS.

DRIVING MECHANISM FOR OSCILLATING PRINTING-PRESSES.

SPECIFICATION forming part of Letters Patent No. 289,558, dated December 4, 1883.

Application filed January 18, 1883. (No model.)

To all whom it may concern:

Be it known that I, FRANCIS H. RICHARDS, a citizen of the United States, residing at Springfield, in the county of Hampden and 5 State of Massachusetts, have invented new and useful Improvements in Driving Mechanism for Oscillating Printing-Presses, of which the following is a specification.

This invention relates to improvements in 10 mechanism for operating oscillating printing-presses, the object being to operate a platen of a press having an oscillating movement by a continuously-rotating shaft combined with one having a reciprocating rotary motion, 15 with which said platen is directly connected, thereby obviating the laborious efforts which are demanded to work said reciprocating rotary shaft by a foot-treadle directly connected therewith.

20 This invention is in the nature of an improvement on the driving mechanism shown in connection with the printing-press in my United States Patent of May 10, 1881, No. 241,421, to which reference may be had.

25 In the drawings forming part of this specification, Figure 1 is a side elevation of a printing-press, illustrating the parts of the latter as shown in Fig. 4 of said patent, substantially, and having applied thereto driving mechanism according to my invention. Fig. 2 is a 30 section through and below the dotted line xx , Fig. 1.

In the drawings, B is the leg-frame of the machine, and D the table, on which are mounted 35 the bed and the platen A, the latter being connected with the crank d' of the shaft h by the rods d . The crank-shaft h is hung in suitable bearings in the frame B, and has secured to one end thereof, outside of said frame, the 40 "mangle-wheel" m . A rotating crank-shaft, n , is hung in frame B, parallel with said shaft

h , one of whose boxes, 7, has a sliding motion, and its opposite box is so fitted as to permit the end of shaft n , which is supported by box 7, to have a motion to and fro while it rotates. 45 The end of shaft n next to the mangle-wheel m projects outside of frame B, and has secured thereto the geared pinion 9, which engages in the usual manner with said wheel m . The opposite end of shaft n has secured thereto the 50 balance-wheel 8, and it is provided with a crank, as shown, with which the foot-treadle 6 is connected by the pitman 5.

The operation of my improved driving mechanism, in conjunction with the platen A 55 of the printing-press, is as follows: The shaft n and the pinion 9 are rotated by the foot-treadle and made to rotate. The engagement of the pinion 9 with the mangle-wheel m gives the latter and shaft h a reciprocating rotary motion, operating the platen A substantially in the manner described relative to the "shaft h " in said patent. The said sliding box 7, supporting the end of shaft n , on which is pinion 9, slides back and forth as the latter is, by 65 the action of the mangle-wheel m , forced to engage first with the outer and then with the inner line of gear-teeth on said wheel, or vice versa.

What I claim as my invention is—

The combination, with the platen A of the printing-press, of the reciprocally-rotating crank-shaft h , connected therewith by the rods d , the mangle-wheel m , secured to said shaft, the rotating crank-shaft n , having the pinion 9 thereon engaging with said mangle-wheel, and the treadle 6 and pitman 5, substantially as set forth.

FRANCIS H. RICHARDS.

Witnesses:

WM. H. CHAPIN,
HENRY KNOX.
